REFRIGERATING APPARATUS

Lawrence A. Philipp, Detroit, Mich., assignor to
 Nash-Kelvinator Corporation, Detroit, Mich., a
 corporation of Maryland

Application November 16, 1940, Serial No. 365,965

2 Claims. (Cl. 62—102)

The present invention relates to refrigerating apparatus and more particularly to such apparatus as is employed for maintaining multiple temperatures.

It is an object of the present invention to provide in a refrigerator a compartment for forced circulation of air through a cooling zone including a finned cooling unit and a motor driven fan for circulating the air over the cooling unit, and a refrigerated freezing section formed as a unitary structure adjacent to the cooling zone.

It is another object of the present invention to provide such a structure in a refrigerator having a freezing chamber and a cooling chamber formed with the top wall of the food storage compartment, the structure being spaced from the front and rear wall of the compartment, and a motor driven fan for circulating the air upwardly along the front wall of the food storage compartment across the cooling coils in the cooling chamber to be deflected and diffused by the rear wall throughout the food storage compartment.

The invention itself, however, both as to its organization and its method of operation, together with additional objects and advantages thereof, will best be understood from the following description of specific embodiments when read in conjunction with the accompanying drawings, in which:

Fig. 1 is a front elevational view of the invention with parts broken away and parts shown in section, and attached to a refrigerator shown in fragmentary cross-section;

Fig. 2 is a side elevational view of the invention embodied in a refrigerator shown in fragmentary cross-section;

Fig. 3 is a cross-sectional view taken along line 3—3 of Fig. 1;

Fig. 4 is a cross-sectional view taken along line 4—4 of Fig. 1 arranged in a refrigerator system shown schematically;

Fig. 5 is a cross-sectional view taken along line 5—5 of Fig. 4; and

Fig. 6 is a fragmentary cross-sectional view taken along line 6—6 of Fig. 2.

Shown in the drawings is a refrigerator cabinet 20 with a food storage compartment 21 having an opening 22 closed by a swingably mounted door 23. The cabinet 20 comprises an inner liner 24 spaced from the outer wall or shell 25 between which is placed suitable heat insulation material 26. The liner 24 forms the walls of the compartment 21. The cabinet 20 may also be provided with a machine compartment (not shown) wherein would be mounted compressor-condenser unit 28 of a refrigerator system connected to the cooling unit 27 secured in compartment 30.

The unit 27 comprises casing 29 forming cooling chamber 30, and a casing 32 forming a freezing chamber 34. The casing 29 is formed with

bottom wall 36, end walls 37, and a front wall 39 secured by bolts and nuts to the end walls. The end walls 37 are secured by bolts and nuts 40 to the underside of the top wall 42 of liner 24 which forms the top wall of the chamber 30. The casing 29 has no rear wall so that the chamber 30 is in open communication with the food storage compartment 22.

The casing 32 is formed with bottom, end, front and rear wall, and is attached by screws 45 passing through the inwardly turned flange 46 of end wall 47 to the bottom wall 36 of casing 29. The front wall of casing 32 is provided with an opening 49 closed by door 50 which is hingedly supported on pin 51 carried by bracket arms 52 secured to end walls 47. A freezing shelf 54 is supportedly secured to the side walls of casing 32. Refrigerant conduit 56 is coiled and bonded in heat exchange relation to the underside of shelf 54.

The front wall 39 has an opening 58 formed by flaring outwardly the metal to provide a circular shell within which is set a fan 59 operated by an electric motor 60. The motor 60 is supported by the stand 62 adjustably secured on a base 63 welded to the bottom wall 36.

Extending longitudinally across the chamber 30 is a cooling coil assembly 65 which includes a refrigerant coil 66 supported between channel shaped frame members 67. The frame members 67 extend vertically in the chamber 30 and are bolted to a respective end wall 37. Fins 70 are thermally bonded to the conduits 66.

The outlet end of cooling coil 66 is connected to the inlet end of the coiled conduit 56 under freezer shelf 54 by a small diameter or restrictor tube 72. The outlet end of conduit 56 is connected to conduit 73 whose opposite end terminates within a tank or accumulator 74. The accumulator 74 is secured by bracket 75 to an end wall 37. Leading from the top of accumulator 74 is return refrigerant conduit 77 whose opposite end is connected to a motor-compressor unit 90 of compressor-condenser unit 28. The outlet end of the motor-compressor unit 90 is connected to condenser 91 which in turn is connected at its bottom outlet to the inlet end of coil 66 by a small diameter capillary conduit 92.

By the operation of the fan 59 the air in the food storage compartment is drawn at a high velocity upwardly along the forward section of the compartment adjacent the door 23, through the opening 58, and into the cooling chamber 30 passing across the cooling coil 66. The cooled air is forced, from the chamber 66, through the rear opening of casing 29 into the compartment 21 to flow along the rear wall to be evenly diffused throughout the food storage compartment.

The partially vaporized refrigerant in coil 66 is metered through restrictor tube 72 into the coil

56 so as to maintain a relatively lower pressure in coil 56 than coil 66. The coil 66 is maintained at a relatively high pressure to provide a correspondingly high temperature so as to cool the circulating air and avoid freezing the moisture which tends to condense from the circulating air upon the fins of the coil 66. The pressure in coil 56 is correspondingly reduced to maintain a freezing temperature for freezing the contents of trays 95 set on the shelf 54.

The gaseous refrigerant in coil 56 is conveyed through conduit 73 into the accumulator 14. From the accumulator the gaseous refrigerant passes through conduit 11 into the compressor unit 90 where it is compressed and discharged into condenser 91 to be condensed. The condensed liquid refrigerant is conveyed and metered through the capillary tube 92 to coil 66. The flow of the refrigerant is solely regulated to the coils 66 and 56 by the capillary tube 92 and restrictor tube 72. The capillary tube 92 is in heat exchange relation with the return vapor conduit 11 for further cooling of the refrigerant flowing to coil 66.

A heat responsive device is provided for controlling the intermittent operation of the motor-compressor unit 90, and comprises a bulb 100 connected by tube 102 to a pressure responsive switch mechanism 104. The bulb 100 is clamped in thermal relation to the frame 67 of cooling coil 66. The switch mechanism 104 is interposed in an electrical circuit (not shown) supplying electrical current for the operation of the motor-compressor unit 90. The bulb 100 is filled with fluid whose pressure varies correspondingly to temperature change effected to operate the opening and closing of the switch mechanism 104 to start or stop the operation of the motor-compressor unit 90 for supplying refrigerant to the cooling unit to maintain the circulating air at a desired temperature value.

A manually operated electrical switch 110 is mounted on the front panel 38 to control the operation of the motor and fan 59. Preferably, the fan is of continuous operation, though, if desired, it may be controlled to operate intermittently with the motor-compressor unit 90 by the switch 104.

A drain pan 120 extends beneath the cooling coil 66 and is supportingly secured to the end walls 37. Moisture from the circulating air, which has condensed on the coil 66, is collected in the pan 120 from which it is drained through conduit 121 to conduit 122 which is connected to a suitable disposal drain outlet.

In the mounting of the cooling coil assembly 65, washers or spacers 130 of heat insulation material are interposed between the frame members 67 and end walls 37 to prevent cooling of the casing 29 by heat conduction. Similarly, the freezing shelf 54 is spaced and insulated from the side walls of casing 32 by spacers 132 of heat insulation material. By this arrangement sweating of the side walls of unit 27 is reduced to a minimum. Should some sweating occur, the moisture is collected in a drain pan 135 suspended beneath the bottom of casing 32. The drain pan 135 extends beyond the side walls of the unit 27 and is supportingly secured to the casing 32. An opening 136 in the bottom wall of casing 32 permits the drainage of the moisture defrosted from

coil 56 to drain from the freezing chamber into the pan 135. The water is drained from pan 135 through conduit 137 into conduit 122.

By this arrangement there is thus provided an evaporator coil operated at relatively low temperature for freezing substances, and a second evaporator coil maintained at a relatively high temperature for cooling the air of a food storage compartment. The desired degree of refrigeration is obtained from the cooling unit operated at a sufficiently high temperature in that the air is circulated at a high velocity over the cooling unit so that the temperature of the air in the food storage compartment is maintained substantially uniform in all positions in the compartment. Further, it avoids freezing moisture condensed from the circulating air. As the moisture is not frozen out of the air as frost, a portion of it returns to the circulating air and its humidity is substantially maintained. The optimum condition is thus substantially maintained for preserving food in the storage compartment and the severe dehydration of the food products avoided.

While I have described the preferred forms of my invention, I do not wish to limit myself to the precise details as shown and described, but wish to avail myself of such variations and modifications as may come within the scope of the appended claims.

I claim:

1. Refrigerating apparatus comprising in combination a cabinet having a food storage compartment, an enclosure member secured within said compartment in spacial relation to front and rear well thereof enclosing an air cooling zone and a low temperature zone, heat absorbing means including a portion positioned in said low temperature zone for maintaining low temperatures in said low temperature zone, and a portion in said air cooling zone for cooling the circulating air as it passes through said air cooling zone, means interconnecting said portions to control the flow of refrigerant therethrough to maintain a relatively low temperature in the first mentioned portion for freezing substances and a relatively high temperature in the second mentioned portion for cooling circulating air, and a fan for directing the flow of air from adjacent the front wall of said compartment through said air cooling zone and along the rear wall of said food storage compartment.

2. Refrigerating apparatus comprising, in combination, a cabinet having a food storage compartment, a sheet metal housing within said compartment having an air cooling compartment and a low temperature compartment separated by a horizontal sheet metal partition, heat absorbing means including a portion positioned in said low compartment in limited heat conducting relation with the walls thereof, said portion being substantially coextensive with the width and depth of said housing, and a portion positioned in said air cooling compartment in limited heat conducting relation with the walls thereof, and means interconnecting said portions to control the flow of refrigerant therethrough to maintain a relatively low temperature in the first mentioned portion for freezing substances and a relatively high temperature in the second mentioned portion for cooling circulating air.

LAWRENCE A. PHILIPP.
